CLAIM

We claim the ornamental design for a personal robot, as shown and described.

DESCRIPTION

FIG. 1 is a front perspective view of a first embodiment of a personal robot showing our new design;
 FIG. 2 is a front view thereof;
 FIG. 3 is a rear view thereof;
 FIG. 4 is a left-side view thereof;
 FIG. 5 is a right-side view thereof;
 FIG. 6 is a top view thereof;
 FIG. 7 is a bottom view thereof;
 FIG. 8 is a rear perspective view thereof;
 FIG. 9 is an exploded view thereof across the horizontal and vertical axis of the personal robot illustrating example internal features; and,
 FIG. 10 is another exploded view thereof.
 The broken lines in the figures depict portions of the personal robot which form no part of the claimed design. The dot-dash broken lines define the boundary of the claimed design and form no part thereof.
